UNITED STATES PATENT OFFICE.

JOSEPH M. DELMORE, OF PIRU, CALIFORNIA.

LOCK FOR SWIVELS.

999,967.

Specification of Letters Patent. Patented Aug. 8, 1911.

Application filed November 28, 1910. Serial No. 594,594.

To all whom it may concern:

Be it known that I, JOSEPH M. DELMORE, a citizen of the United States, residing at Piru, in the county of Ventura and State 5 of California, have invented a new and useful Lock for Swivels, of which the following is a specification.

This invention relates to means for locking the swivels used in well drilling rigs, so 10 as to prevent oscillation of the swivel.

By reason of the twisting of the cable, there is a tendency for the swivel to oscillate or rotate back and forth through a limited angle as the tools are raised and lowered, 15 and the main object of the present invention is to provide simple and effective means to lock the swivel against oscillation due to this twisting action.

A further object of this invention is to 20 provide means for this purpose whereby the locking may be effected by the handles of the handle bar for the temper screw.

Other objects of the invention will appear hereinafter.

The accompanying drawings illustrate the invention, and referring thereto: Figure 1 is a side elevation of the swivel with the temper screw and the upper portion of the drilling cable. Fig. 2 is a vertical section of the swivel. Fig. 3 is a horizontal section in line x^1-x^2 in Fig. 2. Fig. 4 is a horizontal section on line x^3-x^4 in Fig. 2. Fig. 5 is a vertical section on line x^5-x^6 in Fig. 2. Fig. 6 is a perspective of the locking key. Fig. 7 designates the temper screw frame having means such as T 2 at the top for attachment to the usual suspension means and provided with the reins 3 having screw-engagement at 4 at their lower ends with the temper screw 5, clamp 6 being provided to clamp the reins to the screw. The swivel 7 is supported on the head 8 at the lower end of the temper screw by a ball-bearing 9 and is provided with seats 10 for links 11 engaging the rope clamp 12 to support the rope or cable 13. A handle bar 15 is provided with a hub 16 rotatably mounted on a cylindrical portion 17 of the temper screw, one of the arms of said handle bar having a screw-threaded bore 18 to receive a screw 19 extending from a handle member 20 and engaging at its inner end with the cylindrical portion 17 of the temper screw, so that by turning said handle member 20,

the handle bar may be clamped to the temper screw or released therefrom.

The means for locking the swivel comprises a key 21 slidably mounted in a vertical recess 22 in the hub 16 of the handle bar, said recess and key being, for example, dovetailed to retain the key in place and the lower end of said key engaging with serrations or notches 24 in the top of the swivel 7, said key being toothed, as at 26, to engage in a plurality of said notches. 65 For operation of said key, I prefer to use a handle member 27 on the handle bar, the handle members 20 and 27 being at opposite ends of the handle bar and said handle 27 having a spindle 28 extending in a corresponding bore in the other arm of the handle bar and being provided at its inner end with a head 29 having a spiral flange 30 engaging with grooves 31 in the key 21, there being a plurality of these grooves and 75 the said spiral flange engaging successively with the grooves in the rotative movement of the head 29.

The operation is as follows: The height of the tools is adjusted by the rotation of 80 the temper screw, the handle bar being clamped to the temper screw by screwing in the member 20 and the locking key 21 being at this time released from the swivel by proper manipulation of the handle member 27. Such adjustment having been effected, the swivel is locked to the temper screw by turning the handle bar 27, so as to cause the spiral flange 30 to depress the locking key 21 into engagement with serrations 24 in the swivel. Drilling may then be proceeded with and the swivel will be held from oscillation by such engagement of the locking member 21 with the swivel.

It will be noted that the swivel 7 is freely 95 rotatable relatively to the reins 3, except when the key 21 is engaged and the clamp means 6 is tightened. This relative movement or rotation of the parts when disconnected is of importance in manipulation and 100 adjustment of the several parts in bringing the drilling tool to position or removing it from operating position.

What I claim is:

1. The combination with a cable of a 105 swivel connected thereto, a supporting temper screw on which said swivel is rotatably mounted, reins engaging said temper screw,

said swivel being rotatable relatively to the reins, means for tightening the reins on the temper screw, a handle bar rotatably mounted on the temper screw, means for securing said handle bar to the temper screw, and a locking device movably mounted on the handle bar and adapted to engage said swivel to hold the swivel from rotation relatively to the handle bar.

10 2. The combination of a swivel provided with means for attachment and support of a cable and having a notched portion, a temper screw on which said swivel is rotatably mounted, a handle bar attached to said temper screw, and a locking member slidably mounted in said handle bar and adapted to be engaged in said notched portion of the swivel.

15 3. The combination of a swivel provided with means for attachment and support of a cable and having a notched portion, a temper screw on which said swivel is rotatably mounted, a handle bar attached to said temper screw, a key slidably mounted in said handle bar and adapted to be engaged in said notched portion of the swivel, and a

handle member rotatably mounted on said handle bar and provided with means engaging said key to raise and lower the same.

4. The combination of a swivel provided with means for attachment and support of a cable and having a notched portion, a temper screw on which said swivel is rotatably mounted, a handle bar attached to said temper screw, a key slidably mounted in said handle bar and adapted to be engaged in said notched portion of the swivel, and a handle member rotatably mounted on said handle bar and provided with means engaging said key to raise and lower the same, said means comprising a spiral flange carried by said handle member, said key being provided with grooves engaging the said spiral flange.

In testimony whereof, I have hereunto set my hand at Los Angeles California, this 19th day of November, 1910.

JOSEPH M. DELMORE.

In presence of—

ARTHUR P. KNIGHT,
FRANK L. A. GRAHAM.
